UNITED STATES PATENT OFFICE.

WILLIAM D. FORSYTH, DECEASED, LATE OF CLEVELAND, OHIO, BY FLORA I. BURKE,
ADMINISTRATRIX, OF CLEVELAND, OHIO.

ROAD REINFORCEMENT.

Application filed July 5, 1924. Serial No. 724,517.

This invention relates to improvements in metallic re-enforcing means for concrete road structures and the like.

The object of the present invention is to provide an improved metallic net-work reinforcement which is adapted to be embedded in a concrete road or other like structure. This invention comprises a metal net-work which is formed with diamond-shaped openings and diagonals therefor, all of which are formed from an integral sheet of metal which is first slit and then distended into such form. The side walls of the diamond-shaped openings and the diagonals join at the ends and sides of the openings to form channel-shaped bonds all of which lie in substantially the same plane and some of which open in one direction while the others open in the opposite direction.

Fig. 1 is a perspective view of a portion of my improved reenforcement; Fig. 2 is a side view of such a portion; and Fig. 3 is an end view of such a portion, with some of the bonds shown in section.

The side walls or strands 1 of the diamond-shaped openings are clearly shown in the drawings as joining the diagonals 2 so as to form the channel-shaped bonds; the side walls 3 of the bonds joining the strands of the diamond-shaped openings, while the bottoms 4 of the channel-shaped bonds join the diagonals. It is noted that the side walls and bottom of the bonds are substantially normal to each other, or in other words the width of the side walls of the diamonds and that of the diagonals extend in planes substantially normal to each other. It will be noted also that some of the bonds open in one direction while the others open in the opposite direction, as will be clear upon reference to the bonds at the ends of the diamond-shaped openings as compared with those at the sides thereof. All of the bonds lie in substantially the same plane, as clearly indicated.

It will be noted also that the diagonals extend out of the main plane of the net-work so as to form trusses and they afford also a means of support for the reenforcement during the process of pouring the concrete as well as a means of anchoring the reenforcement in the completed road structure. The net-work reenforcement is adapted to

rest upon the flattened portions 5 of the diagonals.

The improved net-work reenforcement is formed from sheet metal which is properly slit and then distended into the form here shown. The side walls of the bonds may be formed either before or during the distending operation. In any event, the side walls or strands of the diamond-shaped openings are bent on lines which are substantially normal to the lines of bending of the diagonals; the particular manner of bending the strands of the diamond-shaped openings and the diagonal strands preventing buckling or crowding of the metal as the sheet is distended into the net-work form. It will be understood that the diagonals extend lengthwise of the road.

Thus such resistance to the distending operation is not only obviated and the operation accordingly facilitated, but this particular form of net-work reenforcement possesses all possible rigidity and strength with the increased reenforcing factor due to the particular arrangement of the strands. Maximum tensile strength is possessed by this reenforcement and it is practically proof against flexing stresses and strains in all directions, so that the danger of the road creeping, buckling, sagging or cracking is practically eliminated. The danger of the reenforcement giving or bending in a direction normal to the road surface is reduced to a minimum by the diamond strands standing on edge, so to speak; and likewise any danger of lateral distortion is obviated especially by the particular arrangement of the diagonals. The diagonals might be regarded as half-diamonds arranged at 90° to the complete diamonds already referred to.

Moreover, this reenforcement, if so desired, may be so placed in a road structure that the upper faces 6 are flush with the top surface of the road, as indicated by the broken line 7, Fig. 2, representing the possible top surface location, with the result that an anti-skidding means is provided.

What is claimed is:

1. A metallic reenforcing structure comprising a diamond mesh, and strands forming diagonals of the diamonds, and extending out of the plane of said diamonds so as

- to form trusses, the width of the walls of the diamonds and the width of the diagonals extending in directions substantially normal to each other.
5. 2. A metallic reenforcing structure comprising a polygonal mesh, and strands forming diagonals of said polygons, the width of the walls of said polygons and the width of said diagonals extending in directions substantially normal to each other.
10. 3. A metallic reenforcing structure comprising a polygonal mesh, and strands forming diagonals of said polygons, the strands of said polygons and those forming the diagonals being joined in such a manner as to form channel-shaped bonds.
15. 4. A metallic reenforcing structure comprising a polygonal mesh, and strands forming diagonals of said polygons, the strands of said polygons and those forming the diagonals being joined in such a manner as to form channel-shaped bonds, some of which open in one direction while others open in the opposite direction.
20. 5. A reenforcing structure comprising an integrally formed sheet metal polygonal mesh and diagonal strands therefor, the width of the walls of said polygons and the width of said diagonals extending in directions substantially normal to each other.
25. 6. A reenforcing structure comprising an integrally formed sheet metal polygonal mesh and diagonal strands therefor, said diagonal strands and those forming the said polygons being joined in such a manner as to form channel-shaped bonds.
30. 7. A metallic reenforcing structure comprising a diamond mesh, and strands forming diagonals of said diamonds, the strands of said diamonds and those forming said diagonals being joined in such a manner as to form channel-shaped bonds with the bonds at the opposite ends of a diamond opening in one direction and the bonds at the opposite sides of a diamond opening in the opposite direction.
35. 8. A metallic reenforcing structure comprising a polygonal mesh, and strands forming diagonals of the polygons and extending out of the plane of said polygons so as to form trusses, the strands of said polygons and those forming said diagonals be-
- ing joined in such a manner as to form channel-shaped bonds, the bottoms of which join the ends of the diagonals.
55. 9. A metallic reenforcing structure comprising a polygonal mesh, and strands forming diagonals of the polygons and extending out of the plane of said polygons so as to form trusses, the strands of said polygons and those forming said diagonals being joined in such a manner as to form channel-shaped bonds, all of said bonds lying in substantially the same plane.
60. 10. An expanded metal mesh comprising metal strips arranged in diamond mesh, the strips forming the sides of the diamond being arranged vertically, and connecting strips lengthwise of the diamonds arranged horizontally, the connecting portions forming open ended cups, the longitudinal connecting strips being bowed out of the plane of the mesh to add vertical depth to the reinforcement.
65. 11. An expanded metal mesh comprising metal strips arranged in diamond mesh, the strips forming the sides of the diamond being arranged vertically, and connecting strips lengthwise of the diamonds arranged horizontally, the connecting portions forming open ended cups, the longitudinal connecting strips being bowed down below the plane of the mesh to add vertical depth to the reenforcement.
70. 12. An expanded metal mesh comprising metal strips arranged in diamond mesh, the strips forming the sides of the diamond, being arranged vertically, and connecting strips lengthwise of the diamonds arranged horizontally, the connecting portions forming open-ended cups, the longitudinal connecting strips being bowed down below the plane of the mesh to add vertical depth to the reenforcement, all such cups in the same longitudinal and transverse lines being open in the same direction, but cups in adjacent longitudinal and transverse lines being open in the opposite direction.
75. In testimony whereof I hereby affix my signature.

FLORA I. BURKE,
Administratrix of Estate of William D. Forsyth, Deceased.
